UNITED STATES PATENT OFFICE.

GEORGE W. BEADLE, OF NEW YORK, N. Y., ASSIGNOR TO MERGENTHALER LINOTYPE COMPANY, A CORPORATION OF NEW YORK.

KEYBOARD MECHANISM.

Application filed August 13, 1926. Serial No. 128,918.

This invention has reference to keyboard mechanisms, such as are employed in commercial linotype machines. In these machines, the escapements controlling the discharge of the matrices from the magazine are ordinarily actuated by vertical reeds operated by pivoted yokes or levers, each containing a rotary cam or eccentric which is adapted to make peripheral contact with an underlying constantly rotating rubber-covered roll. The pivoted yokes are held normally with their cams at rest and out of contact with the rubber-covered roll and are released by the manipulation of finger keys, which permit the cams to fall into engagement with the driving roll and be rotated thereby to raise the yokes and operate the escapements. In practice, the life of the rubber-covered rolls is comparatively short by reason of wear and other deteriorating influences, and hence it is necessary at times to remove the worn rolls and substitute new ones, involving considerable expense and occasioning much inconvenience and loss of time. In addition, the wear of the rolls oftentimes results in the failure of the escapements to respond to the actuation of the finger keys, due to the insufficient raising of the cam yokes. Furthermore, and without regard to the question of wear, considerable slippage takes place between the cams and the rubber-covered rolls during their driving engagement, and especially when oil finds its way onto the rolls, resulting in a delayed actuation of the matrix-releasing escapements, and thus giving rise to transpositions of matrices in the composed line.

The present invention is intended to do away with the rubber-covered rolls and their attendant objections, and contemplates a simple, compact arrangement wherein the cams or eccentrics are rotated positively and their engagement and disengagement with and from the driving roll accomplished in a direct and reliable manner. In the embodiment illustrated, the cams are loosely mounted on a metal driving roll and are provided with key-controlled clutch members acting to couple the cams to or uncouple them from the driving roll, the latter being formed with one or more grooves to receive teeth formed on the clutch members in providing

for the driving engagement between the parts.

In the accompanying drawings, the invention has been shown merely in preferred form and by way of example and as applied to a linotype machine, but obviously many changes and variations may be made therein and in its mode of application which will still be comprised within its scope. It should be understood, therefore, that the invention is not limited to any specific form or embodiment except in so far as such limitations are specified in the claims.

In the drawings:

Fig. 1 is a side elevation, partly in section and broken away, of the improved keyboard mechanism as applied to a linotype machine and showing the keyboard parts at rest;

Fig. 2 is a similar view showing the keyboard parts in operation;

Fig. 3 is a vertical transverse section taken on line 3—3 of Fig. 1; and

Fig. 4 is a detail perspective view of one of the cam units.

As shown in Fig. 1, the matrix releasing escapements A are actuated by a series of vertically disposed levers A¹ through the medium of a corresponding series of rocking levers A² arranged between the upper ends of the levers A¹ and the escapement plungers. The lower ends of said levers A¹ are provided with anti-friction rollers A³ arranged to ride upon rotatable cams or eccentrics B, against which they are yieldingly maintained by pull strings A⁴ connected to the upper levers A². As the parts are thus arranged, the cams B when rotated will rock the levers A¹, A² and actuate the associated escapements A to effect the release of the corresponding matrices X, which then pass from the magazine F into the assembler throat E for composition in line in the usual way.

The cams B, according to the present invention, are loosely mounted on a constantly driven metal roll B¹ but are capable of being connected to and disconnected from said roll by means of curved clutch pawls B² pivoted at b to the sides of the cams. The cams B are provided with laterally extending flanges or hubs B³ which serve to main-

tain the cams in uniformly spaced relation on the driving roll B^1 and also to provide sufficient clearance for the pawls B^2 to turn freely about their pivotal axes b . These pawls B^2 are each formed with a tooth B^4 projecting inwardly therefrom and arranged to engage with one or the other of a pair of diametrically opposite grooves B^5 formed in the roll B^1 and extending throughout the length thereof. Plate springs B^6 , anchored to the cams B and pressing against one end of the attached pawls B^2 , tend constantly to draw the teeth B^4 into engagement with the grooves B^5 , it being noted that the hubs B^3 are notched or cut away to permit passage of the teeth therethrough. At their opposite ends, however, the pawls B^2 bank upon pivoted trip dogs C which hold them normally disengaged from the driving roll against the tension of the spring B^6 . These trip dogs, as usual, are controlled by finger keys C^1 through a series of vertical connecting bars C^2 slidably mounted in the keyboard frame.

25 The operation of the parts is as follows: When a finger key C^1 is depressed, the connected bar C^2 is lifted and the corresponding trip dog C rocked forwardly from under the clutch pawl B^2 (see Fig. 2). The spring B^6 acts instantly to draw the pawl tooth B^4 into driving engagement with one of the roll grooves B^5 . The appropriate cam B is thus caused to rotate with the driving roll B^1 and, as it continues to rotate, the associated lever A^1 is rocked rearwardly to the position shown by the broken lines in Fig. 2 and, through the lever A^2 , caused to actuate the escape-
30 ment A for the release of a matrix corresponding to the finger key actuated. In the meantime, due to the release of the finger key, the free end of the trip dog C will have returned to its normal position, so that when the cam has about completed its rotation, the clutch pawl B^2 will engage the dog C and its tooth B^4 be lifted out of groove B^5 , thereby breaking the driving connection between the rotating roll B^1 and the cam B and allowing the latter to come to rest to await the next actuation of the finger key (Fig. 1).

35 Many advantages characterize the improved construction. In addition to those previously mentioned, it may be noted that the mechanism is compact, self-contained, easily assembled, and inexpensive to manufacture. Moreover, a single bank or row of the cam units will suffice for all the finger keys.

40 As before stated, the foregoing improvements have been shown merely in preferred form and by way of example, and obviously many changes and variations may be made without departing from the spirit of the invention. For example, the number of grooves in the roll B^1 might be materially increased and even to the extent of making the

roll substantially in the form of an elongated gear or ratchet. It is obvious, also, that instead of the rocking levers A^1 , vertical reciprocating reeds of the ordinary type could be used by mounting them above and in contact with the cams B . These and various other changes will readily suggest themselves to those skilled in the art.

Having thus described my invention, its construction and mode of operation, what I claim and desire to secure by Letters Patent of the United States, is as follows:

1. In a mechanism of the class described, the combination of a rotary driving element, a rotary driven element mounted loosely thereon and rotatable concentrically thereof but capable of connection therewith, an actuating member associated with the driven element, and means for controlling the connection and disconnection of said element with and from the driving element.

2. In a mechanism of the class described, the combination of a rotary driving element, a rotary driven element normally disconnected therefrom and rotatable concentrically thereof, a clutch for establishing a driving connection between said elements, an actuating member associated with the driven element, and means for engaging and disengaging the clutch as required.

3. In a mechanism of the class described, the combination of a rotary grooved driving element, a rotary driven element, a pivoted clutch pawl carried by the driven element, an actuating member associated with the driven element, and controlling means whereby the clutch pawl may be engaged with and disengaged from the grooved driving element as required.

4. In a mechanism of the class described, the combination of a rotary driving element, a cam loosely mounted thereon and rotatable concentrically thereof, a clutch for connecting the cam to or disconnecting it from the driving element, an actuating member associated with the cam, and means for engaging and disengaging the clutch as required.

5. In a mechanism of the class described, the combination of a rotary driving element, a cam loosely mounted thereon, a pivoted clutch pawl carried by the cam and engageable with said driving element, an actuating member controlled by the cam, and means for making and breaking the engagement of the clutch pawl with the driving element as required.

6. In a keyboard mechanism of the class described, the combination of a power-driven roll, a cam loosely mounted thereon and rotatable concentrically thereof, a key-actuated trip dog, and a clutch controlled by said dog for making and breaking the connection between the roll and cam.

7. In a keyboard mechanism of the class

described, the combination of a power-driven roll, a cam loosely mounted thereon, a key-actuated trip dog, and a pivoted clutch pawl carried by the cam and controlled by said dog for making and breaking the driving connection between the roll and cam:

8. In a keyboard mechanism of the class described, the combination of a power-driven roll, a series of cams loosely mounted thereon and rotatable concentrically thereof but capable of connection therewith, a corresponding series of actuating members associated with the respective cams, and means for controlling the connection and disconnection of the cams individually with and from the roll.

9. In a keyboard mechanism of the class described, the combination of a power-driven roll, a series of cams loosely mounted thereon, a corresponding series of actuating members associated with the cams, pivoted clutch

pawls carried by the respective cams for establishing a driving connection between the cams and roll, and controlling means whereby the clutch pawls may be individually engaged with and disengaged from the power-driven roll as required.

10. In a keyboard mechanism of the class described, the combination of a grooved power-driven roll, a series of cams loosely mounted thereon and formed with hubs for maintaining them in uniform spaced relation, spring-actuated pivoted clutch pawls carried by the respective cams, and key-actuated trip dogs whereby the clutches may be individually engaged with and disengaged from the grooved power-driven roll as required.

In testimony whereof, I have affixed my signature hereto.

GEORGE W. BEADLE.
